UNITED STATES PATENT OFFICE.

BENJAMIN W. KLEIN, OF MOUNT VERNON, NEW YORK.

POWER-TRANSMISSION DEVICE.

Application filed March 3, 1922. Serial No. 540,923.

To all whom it may concern:

Be it known that I, BENJAMIN W. KLEIN, a citizen of the United States, and resident of Mount Vernon, county of Westchester, 5 and State of New York, have invented certain new and useful Improvements in Power-Transmission Devices, of which the following is a specification.

This invention relates to an improved 10 power transmission device and in its generic aspect contemplates the provision of means for transmitting power from a single motor or other prime mover to a pair of tools and permitting of a universal movement or 15 manipulation of the tools relative to each other and with respect to the motor, while maintaining a continuous maximum power transmission from the motor to the tools.

More particularly, my present improvement 20 comprehends, in a device of the above character, a positive geared connection between the motor shaft and a flexible tool operating shaft which is mounted for universal swinging or pivotal movement with 25 respect to the motor shaft whereby lost motion in the driving connection is practically eliminated and a continuous smooth and unbroken transmission of power to the tool operating shaft in the various angular 30 positions which the latter may assume, is obtained.

In a practical embodiment of the present invention, such as that illustrated in the accompanying drawings, I have shown my 35 present improvements as applied to a shoe polishing machine for the purpose of expediting the polishing of shoes. I am aware of the fact that it is not new to provide a motor driven polishing brush to be manually manipulated, but the use of such a single 40 brush consumes considerable time and owing to the wide range of movement which is necessary in order to apply the brush to all parts of the shoe, it is not uncommon for the 45 flexible shaft connected to the motor to be so twisted that the shaft is broken. Therefore, I propose to operate two such rotary brushes or applicators from the single motor heretofore employed and to provide a uni- 50 versally movable connection between the flexible driving shafts and the brushes with a positively geared connection between said shafts and the ends of the motor shaft.

Thus the two brushes may be simultaneously 55 moved along opposite sides of the shoe and the polishing of the shoe quickly completed

with a minimum of manual labor and with an economical consumption of the motor power and the assurance that the flexible driving shafts will not be unduly twisted 60 and possibly broken.

It is also a particular object of my present invention to provide an improved pivotal mounting or connection between the motor and the driving shaft with relatively movable housing or guard sections which serve 65 to prevent parts of the clothing coming in contact with the gears or other foreign objects lodging thereon and interfering with their proper operation.

With the above and other objects in view, the invention consists in the improved power transmission device and in the form, construction and relative arrangement of the several parts as will be hereinafter more fully 70 described, illustrated in the accompanying drawings and subsequently incorporated in the subjoined claim.

In the drawings wherein I have disclosed one practical and satisfactory embodiment 75 of the invention and in which similar reference characters designate corresponding parts throughout the several views,

Fig. 1 is a front elevation showing my present improvements as adapted for use in 80 connection with a shoe polishing machine;

Fig. 2 is an enlarged detail sectional view 85 illustrating the geared driving connection between the motor shaft and the driving shaft;

Fig. 3 is a section taken on the line 3—3 of Fig. 2;

Fig. 4 is an enlarged longitudinal section 90 through the hand-hold showing the connections between the flexible driving shaft and the brush or other tool;

Fig. 5 is a detail sectional view of the brush with the means for detachable connection to the driving shaft;

Fig. 6 is a view illustrating a slight modification showing the brush in section and disconnected from the driving shaft, and

Fig. 7 is an end elevation of the brush shown in Fig. 6.

In the drawings I have shown an electric 105 motor 5 which may be of any preferred type using either direct or alternating current. The armature shaft 6 of the motor extends axially in opposite directions from the sides of the motor case, and each end of the shaft 110 has a reduced threaded extension 7 to receive a cog gear 8 having its teeth 9 disposed at

an angle of substantially 45° with respect to the axis of the motor shaft. These gear teeth are of the peculiar form shown in the drawings, the outer end portions being 5 rounded or convex as at 10 and describing a continuous arc.

Upon each end portion of the motor shaft 6 a bearing sleeve 11 is disposed, said sleeve having a bronze bushing 12 extending the 10 full length thereof in direct bearing contact with the motor shaft. The outer end of the sleeve 11 is formed with a head 13 which is formed at its upper side with the forwardly projecting arms 14 and 15 respectively, said arms being located at opposite sides of the shaft 6 and at relatively different distances therefrom. The arm 14 is provided with a laterally projecting stud 16 disposed at an angle of 90° with respect 20 to the motor shaft 6.

The flexible driving shaft 17 for the rotary tool may be of any approved construction and at one of its ends is journaled in the bronze bushing 18 of the bearing head 25 19, said end of the flexible shaft also having a reduced threaded extension 20 upon which the cog gear 21 is engaged against one side of the bearing head 19. This gear 21 is of precisely the same form as the gear 8 30 above described.

The bearing head 19 is likewise provided at one side thereof with the arms or extensions 22 and 23 which correspond respectively with the arms 14 and 15 on the bearing head 13, the arm 22 having a stud 24 similar to the stud 16. The arms 15 and 23 of the two bearing members are provided with openings to loosely receive the studs 24 and 16 respectively, so that the 40 bearing head 19 may freely swing or pivot on said studs, thus permitting the flexible driving shaft 17 to move to various angular positions with respect to the motor shaft as indicated by the arrows A in Fig. 2 of 45 the drawings.

It is to be noted that the aligned pivot studs 16 and 24 have their axial centers disposed in coinciding relation with the center pitch lines of the teeth of the gears 8 and 50 21. Therefore, it will be obvious that the teeth of these gears will at all times be in intermeshing relation, regardless of the angular position which the flexible driving shaft may assume and that there will be no 55 interruption in the continuity of the driving force transmitted through said gears from the motor shaft to the driving shaft.

To each of the flexible driving shafts 17 connected to the ends of the motor shaft in 60 the manner just explained, rotary tools may be interchangeably connected, and these tools may thus be independently manipulated to operate upon different portions of an object at the same time. In Figs. 1 and 65 1 of the drawings I have shown each flexible

driving shaft provided at its free end with a knurled hand-hold 25 in the form of an elongated sleeve having a threaded connection 26 at its inner end to a bearing member 27 for the end 28 of the flexible shaft. This bearing member is internally threaded at one end to receive the externally threaded extension 30 of a sleeve 29 which is fitted within the hand-hold 25. A spindle 31 extends through said sleeve and is rotatably 75 engaged in the extension 30 thereof, said spindle having a flange 32 on one end engaging over the end of the extension 30. This spindle is provided with a longitudinal bore 33 to receive a longitudinally extending pin 34 on the end 28 of the flexible shaft, said pin being of semi-circular form in cross-section and having a flat longitudinally inclined face 35 with which a correspondingly inclined face of a key 36 is engaged. This key is removably secured within the bore 33 by suitable screws 37.

Between the spindle 31 and the forward end of the sleeve 29 a suitable ball-bearing 38 is interposed, said spindle terminating in a reduced threaded extension 39 to which a retaining collar 40 for the ball-bearing is fixed. Upon the threaded extension 39 a sleeve 41 is detachably engaged and extends longitudinally through the open end of the hand-hold 25. The outer end of this sleeve is longitudinally split as at 42 to provide a plurality of radially resilient sections.

The rotary tool, which as herein shown, is in the form of a polishing brush 43, has its core longitudinally bored to receive the end of a shaft 44 which, as illustrated in Fig. 5, may be secured to said bore by means of a key or pin 45. The projecting end of this shaft has a longitudinally reduced portion affording a transverse shoulder 46. This end of the tool shaft is adapted to be inserted in the split end of the sleeve 41 until the shoulder 46 contacts with the stop pin 47 extending transversely through the bore of said sleeve. The diameter of the shaft 44 is slightly greater than the split end of the sleeve 41 so that said split portions will exert an inward holding pressure upon said shaft to detachably retain the same in connection with said sleeve.

In Figs. 6 and 7 of the drawings I have shown an alternative means for detachably connecting the brush or the tool to the flexible driving shaft. In this case the sleeve 41 instead of being split at its outer end is provided with a solid rectangular extension 48 projecting beyond the end of the hand hold and having its extremity tapered as at 49. The brush core 50 is of rectangular form and is axially bored to receive the square shaft extension 48. At one end of said bore the core 50 is recessed to receive the spring clip 51 which is retained in said recess by means of the metal cap 52 fixed to the end 130

of the brush core. As seen in Fig. 7 of the drawings, the opposite side portions of the clip 51 are normally bowed inwardly towards each other. Thus, when the shaft 5 extension 48 is forced into the bore of the brush core, these side portions of the retaining clip will be pressed outwardly and placed under tension, said clip portions exerting a clamping pressure against opposite sides of the shaft 48, and thus detachably holding the brush in connection therewith.

In the practical application of my present invention as illustrated in Fig. 1 of the drawings, the motor 5 is suitably secured to a floor or base beneath a platform or stand 53 upon which a series of spaced stools or seats 54 may be arranged. Beneath each of these seats a foot rest 55 is secured to the front edge of the platform 53. At each side of the stool or seat 54 a suitable support 56 is arranged for detachably receiving the end of one of the hand-holds 25 when the device is not in use.

In operation, the patron seats himself on the stool 54 and places one foot on the rest 55. After applying the paste or other polishing composition to the surfaces of the shoe, the motor 5 is started in operation and the operator grasping the hand-holds 25 moves the polishing brushes 43 rapidly over the opposite sides of the shoe at the same time. In manipulating these polishing brushes the shaft 17 is freely flexed so as to permit the rotary axis of the brush to be disposed at various angles and enable the periphery of the brush to be engaged with all portions of the shoe surface. This freedom in the manipulation of the brushes or tools without injury to the flexible driving shafts is due to the manner of mounting and connecting the shaft bearings with respect to the motor shaft, as above explained. In addition to permitting the swinging or pivotal movement of the flexible shafts in the direction indicated by the arrows A in Fig. 2 without disconnecting the driving gears, said shafts may also move in the direction indicated by the arrows B in Fig. 3 of the drawings, the bearing sleeves 11 turning freely on the motor shaft. Thus the operation of providing a high polish upon the surfaces of the shoe may be greatly expedited by means of my present invention.

Obviously a very small amount of electric current is consumed in this operation and in practice a one-eighth H. P. motor will suffice to drive the polishing brushes at the desired speed. Of course it will be understood that other tools may be interchangeably used in connection with the flexible shafts for performing various other operations.

In order to obviate the possibility of portions of the dress or clothing catching in the intermeshing gears 8 and 21 and for

protecting these gears against possible injury, I provide the guard or housing sections 57 and 58 respectively. These sections are each loosely engaged upon the pivot studs 16 and 24 at the outer sides of the bearing arms 15 and 23, and as will be noted from reference to Fig. 2 of the drawings, the section 58, has its lower edge disposed within the guard section 57. The guard section 57 is formed with a flange 59 engaging behind the shoulder 60 on the bearing head 13 and the guard section 58 is provided with a similar flange 61 engaged with the shoulder 62 on the bearing head 19. Thus it will be understood that these guard or housing sections have no pivotal movement independently of the bearing heads. However, as the flexible shaft 16 is moved to different angular positions with relation to the motor shaft, the guard section 58 will swing with the bearing 19 and move freely into and out of the complementary guard section 57. In the manipulation of the rotary brush or tool, there may momentarily be an open space or gap between the opposed ends of these guard sections, but when the tools have been engaged in the supports 56, it will be observed that the outer side of the housing is completely closed and the gear elements entirely covered thereby.

From the foregoing description considered in connection with the accompanying drawings, the construction and manner of operation of my improved power transmission device will be completely understood. I have herein made reference to one advantageous application of my present improvements, but it will be manifest that the invention might also be utilized in connection with various other operations where it is desirable and advantageous to operate upon the work or object with two independently manipulable tools. By reason of the manner in which the motor shaft and the driving shafts are mounted and correlated so that there is continuous positive meshing engagement between the power transmission gears, unbroken continuity in the transmission of maximum power from the motor to the driving shaft is obtained. By the elimination of direct connection of the flexible driving shaft to the motor shaft, the possible breakage of the driving shaft by excessive bending or twisting of the same is precluded and a maximum freedom of angular movement of the flexible driving shaft in all directions is obtained.

While I have herein disclosed one satisfactory and practical embodiment of my present invention, it is nevertheless to be understood that the device is susceptible of embodiment in numerous other alternative constructions and I accordingly reserve the privilege of resorting to all such legitimate changes in the form, construction and rela-

tive arrangement of the several parts as may be fairly embodied within the spirit and scope of the invention as claimed.

I claim:

5 In combination with a motor having a shaft extension, a flexible tool operating shaft, an end bearing for said flexible shaft, a bearing part loosely mounted for axial rotation on the motor shaft extension, each of said bearing parts having arms located at opposite sides of the axial center of the bearing and unequally spaced therefrom, one of the arms being provided with a pivot stud and the other 15 arm having an opening to receive the pivot stud of the other bearing part whereby the bearing part for the flexible shaft may be

connected to or disconnected from the bearing part on the motor shaft by a relative shifting movement, and intermeshing gear elements detachably connected to the ends of the motor shaft and the flexible shaft to continuously drive the latter in its angular movement with respect to the motor shaft and said gear elements coacting with the respective bearing parts and constituting stops to prevent shifting movement of said parts in one direction upon the respective shafts.

In testimony that I claim the foregoing 30 as my invention, I have signed my name hereunder.

BENJ. W. KLEIN.
